(57) **CLAIM**

The ornamental design for a food container as shown and
described.

DESCRIPTION

FIG. 1 is a top, left perspective view of a first embodiment
of a food container showing our new design;

FIG. 2 is a bottom, right perspective view thereof.

FIG. 3 is top view thereof.

FIG. 4 is a bottom view thereof.

FIG. 5 is a front view thereof.

FIG. 6 is rear view thereof.

FIG. 7 is a left view thereof.

FIG. 8 is a right view thereof.

FIG. 9 is a top, left perspective view of another embodiment
of a food container of our new design.

FIG. 10 is a bottom, right perspective view thereof.

FIG. 11 is top view thereof.

FIG. 12 is a bottom view thereof.

FIG. 13 is a front view thereof.

FIG. 14 is rear view thereof.

FIG. 15 is a right view thereof; and,

FIG. 16 is a left view thereof.

The broken lines represent unclaimed subject matter and
form no part of the claimed design.

1 Claim, 8 Drawing Sheets
